UNITED STATES PATENT OFFICE

157,298

CARCASS SPLITTING SAW

Ezekiel C. Steiner, Los Angeles, Calif.

Application August 18, 1948, Serial No. 148,159

Term of patent 14 years

(Cl. D11—1)

To all whom it may concern:

Be it known that I, Ezekiel C. Steiner, a citizen of the United States, residing at Los Angeles, California, have invented a new, original, and ornamental Design for a Carcass Splitting Saw, of which the following is a specification, reference being had to the accompanying drawing, forming part thereof.

In said drawing,

Fig. 1 is a top plan view of a carcass splitting saw, showing my new design.

Fig. 2 is a side elevational view thereof.

Fig. 3 is an elevational view of the opposite side.

I claim:

The ornamental design for a carcass splitting saw, substantially as shown.

EZEKIEL C. STEINER.
